(57) **CLAIM**

The ornamental design for a water wheel and well, as shown and described.

DESCRIPTION

FIG. 1 is a perspective right side view of a water wheel and well showing my new design.

FIG. 2 is a perspective left side view of the water wheel and well of FIG. 1; and,

FIG. 3 is a front view of the water wheel and well of FIG. 1. The broken lines are for illustrative purposes only and form no part of the claimed design.
